UNITED STATES PATENT OFFICE.

WILLIAM V. HEINZ, OF LA SALLE, ILLINOIS.

CHUTE FOR GLAZED WINDOWS.

1,110,627.

Specification of Letters Patent. Patented Sept. 15, 1914.

Application filed April 10, 1913. Serial No. 760,123.

To all whom it may concern:

Be it known that I, WILLIAM V. HEINZ, a citizen of the United States, residing at La Salle, in the county of La Salle and State of Illinois, have invented a new and useful Chute for Glazed Windows, of which the following is a specification.

My invention relates to chutes used for conducting coal or the like through a window into a storage room, and in which the chute is automatically moved and held in proper position for use when the window is opened; and the objects of my improvements are first, to so arrange and connect the window, chute and a fender that the opening of the window will move the chute and fender into the desired position for use of the chute and the closing of the window will move the said parts to the closed position; second, to have the chute and fender normally in a position to permit the light to come through the window unobstructed; third, to have the glass in the window protected against breakage when the chute is being used; fourth, to provide a novel hinge for the window to lock it in an open position; fifth, to make a cheap, simple, durable and easy working construction and other features to become apparent from the description to follow.

Chutes for the purpose of delivering coal or the like through windows when shoveling the same from a wagon are preferably arranged just inside of the window opening in such position that the light from the outside can pass through the window and enter the building unobstructed and at the same time be convenient to place into position for use. A chute made in accordance with my invention embodies these desirable features; and comprises a chute connected to the free end of a swinging window by means of two parallel side bars between which is arranged a sheet metal fender to protect the glass in the window against accidental breakage when the window is open. I also provide a simple and strong set of hinges on the window which is preferably made of metal, which hinges are made to automatically lock the window in an open position.

To describe my invention so that others versed in the art to which it pertains can make and use the same, I have illustrated

it on the accompanying two sheets of drawings forming a part of this specification, 55 and in which:

Figure 1 is an outside front elevation of a window equipped with my invention, showing the window and chute in a closed or normal position; Fig. 2 is a similar view showing the window open and the chute in a position for use. Fig. 3 is a vertical sectional view taken on line 3—3 of Fig. 1; Fig. 4 is a similar view taken on line 4—4 of Fig. 2; Fig. 5 is a perspective view of one member of the hinge detached and enlarged; Fig. 6 is a similar view of the other member of the hinge; and Fig. 7 is a side elevation of the complete hinge enlarged showing the connected parts.

Similar reference characters refer to similar parts throughout the several views.

The wall of a building is represented at 8 and is provided with the window opening 9 which is normally closed by the sash 10, 75 hinged at its upper edge to the window frame 11. The sash 10 is provided with a pane of glass 12 to permit the daylight from the exterior to enter the building.

The hinge connection between the sash 10 80 and the frame 11 comprises the member 13 rigidly connected to or integral with the frame 11, and the member 14 rigidly connected to or integral with the sash 10.

As shown in Fig. 5, the member 13 is of 85 a circular contour and is provided with an interrupted circular laterally-extending flange 15 to form a small slot 16 at the bottom and the large gap 17 at the top. As shown in Fig. 6, the member 14 is also 90 of a circular contour preferably of the same diameter as the member 13, and is provided with a central laterally extending hub or boss 18 provided with the integral upwardly extending lug 19. The greatest dimension 95 across the boss 18 and lug 19 is such that said parts will fit loosely within the confines of the interrupted flange 15 on member 13, as indicated by dotted lines in Fig. 7, and are turned in same to act as a pivot 100 about which the sash 10 swings. The members 13 and 14 thus co-operating together form a hinge, of which there are two provided on the sash 10. The two members 14 on the sash are arranged on opposite 105 sides of the two members 13 on the frame

so that the sash cannot be moved laterally or sidewise to disengage the members 13 and 14.

In operation as the sash 10 is swung from its lower closed position to its upper open position the lugs 19 will move to a position below the pivotal point of the sash and will enter the slots 16, the weight of the sash forcing the said lugs 19 into said slots 16. 10 The sash is thus locked in its upper or open position; and to again swing it into its closed position it must first be lifted slightly to withdraw the lugs 19 from the slots 16. I preferably arrange a lug 20 integral with 15 the member 14 in a plane just outside the flange 15 to enter the gap 17 when the sash 10 is swung to its upper open position. Thus it will be seen that both lugs 19 and 20 contribute alike to locking the sash. 10 20 in an open position, the lug 19 entering slot 16 and the lug 20 entering the gap 17.

Pivottally connected to the free end of the sash 10 are the ends of two links 21 which have their other ends, which are bent 25 in an angle, pivottally connected to the opposite sides of the chute 22 at 23. The shape and length of the links 21, the size of the chute 22 and the position of the pivots 23 are such that when the sash is in a closed 30 position the parts will assume the position shown in Fig. 3, and when the sash is in an open position the parts will assume the position shown in Fig. 4. Suitable stops 24, preferably in the shape of hooks, are provided 35 on the opposite sides of the chute 22 against which the bent portions of the links 21 take when the sash is in an open position. The stops 24 are so positioned that the chute 22 will be slightly tilted to 40 ward the window when the sash 10 is in an open position as shown in Fig. 4. A sheet metal fender 25 is riveted to the two links 21 and spans the space between them to form a protection for the glass 12 when 45 the sash 10 is in an open position as shown in Figs. 2 and 4.

It will be noted that, when the sash 10 is in a closed position as seen in Fig. 3, the fender 25 and the chute 22 are in such position inside the building, as will not obstruct the rays of light coming in through the glass 12; and when the sash 10 is in an open position as seen in Fig. 4, the fender 25 is directly in front of the glass 12 and 55 the chute is projecting partly outside of the window so that coal or other material can conveniently be thrown into the same.

Thus when the glazed sash is in a closed position the fender and chute are in a position to permit the light to enter the building unobstructed, and as the sash is opened the fender and chute are automatically moved to their proper positions respectively, i. e., the fender to a position in front of the 65 pane of glass and the chute to a position

partly outside of the window; while the novelly-constructed hinges automatically lock the sash in its open or vertical positions.

It will be understood that numerous 70 changes may be made in the size and construction of the parts without in the least deviating from the scope of the invention.

What I claim as new and desire to secure by Letters Patent of the United States is— 75

1. In a device of the class described, a window casing, a sash hinged to the casing for opening or closing the window, a chute slidably mounted within the casing arranged to lie either entirely within the casing or 80 projecting partly out of the casing, and a pair of suitable links having one end pivoted to the inner portion of the chute and the other end pivoted to the swinging part of the sash, the parts being so constructed and 85 arranged that the upturning of the sash about its hinges will cause the chute to move from its position entirely within the casing to its position partly projecting out of the casing. 90

2. In a device of the class described, a window casing, a glazed sash hinged to the casing for opening or closing the window, a chute slidably mounted within the casing arranged to lie either entirely within the 95 casing or partly projecting out of the casing, suitable links connecting the chute to a swinging part of the sash, and a suitable fender for the glazed sash carried by the links, the parts being so constructed and 100 arranged that the swinging of the sash to and from its hinged connection with the casing will cause the fender and the chute to move into and from their operative positions. 105

3. In a device of the class described, a window casing, a glazed sash on the casing, pivoted to open and close, a chute slidably mounted within the casing arranged to lie either entirely within the casing or projecting partly out of the casing, a pair of suitable links having one end pivoted to the chute and the other end pivoted to the swinging part of the sash, and stops on the chute to engage the links and cause the chute to be 110 tilted when the sash is upturned to the vertical. 115

4. In a device of the class described, a window casing, a sash frame hinged to the casing, a chute slidably mounted within the 120 casing, a pair of suitable links having one end pivoted to the chute near its inner end and the outer end pivoted to the swinging part of the sash frame and a locking means to automatically lock the sash frame when it 125 is swung to an open position.

5. In a device of the class described, a window casing, a sash frame hinged to the casing, a chute slidably mounted within the 130 casing and adapted to lie either entirely

within the casing or partly projecting out of the casing, a pair of angular links having one end pivoted to the chute near its inner end and the other end pivoted to the swing-
5 ing part of the sash frame and suitable stops on the chute to engage the links, whereby the chute is moved outwardly and tilted upwardly in the casing by the upturning of the sash and is moved inwardly and re-
10 stored to its prone position by the down-
turning of the sash.

6. In a device of the class described, a window casing, a sash hinged at its top to the top of the casing, a chute arranged 15 within the casing and adapted to slide horizontally and tilt within the same, a pair of angular links arranged within the chute and having their innermost ends pivoted thereto near the front end, and stops arranged to coöperate with said links and cause them to be pulled back in the casing
20

and tilted when the links are upturned toward the front as described.

7. In a device of the class described, a window casing, a glazed sash hinged at its 25 top to the top of the casing, a chute arranged within the casing and adapted to slide horizontally therein and to tilt therein, a pair of angular links arranged within the chute and having their innermost ends piv- 30 oted thereto near the front end, a fender carried by said links and stops for checking the movement when the links are upturned.

In testimony whereof I have signed my name to this specification in the presence of 35 two subscribing witnesses this 31st day of March, 1913, at La Salle, Illinois.

WILLIAM V. HEINZ.
